UNITED STATES PATENT OFFICE.

SELDEN L. STONE AND ROY C. BRAENDLEIN, OF INDIANAPOLIS, INDIANA.

TIME SWITCH.

Application filed May 8, 1922. Serial No. 559,140.

To all whom it may concern:

Be it known that we, SELDEN L. STONE and ROY C. BRAENDLEIN, citizens of the United States, residing at Indianapolis, in the county of Marion and State of Indiana, have invented certain new and useful Improvements in a Time Switch, of which the following is a specification.

This invention relates to a system for controlling the lamps for illuminating advertising bill boards, lamps for motor cars, and all places where it is necessary to open and close electric circuits at intervals, the said system contemplating the use of suitably arranged electric conductor wires; lamps within the circuit for illuminating purpose, and also certain timing mechanism adapted to open or close the electric circuit in the system at stated intervals.

One of the objects of the invention consists in the provision of a lighting system for the purposes above specified wherein the electric circuit may be opened or closed at determined intervals throughout a considerable period of time, thereby avoiding the daily attendance of an operator and effecting thereby a saving in operating expenses, by reducing the number of employees necessary for the manual operation of such lighting systems especially when these systems are located at widely separated places, as in the case of advertising bill boards.

A further object of the invention is its ready adaptability for use in connection with the lighting systems of motor vehicles, wherein it is necessary to light the lamps at a different hour as the days lengthen and shorten during the year, to comply with traffic ordinances, thereby eliminating annoyances and waste of time on the part of the motoring public.

A still further object of the invention consists in the provision of a time switch, constituting an essential part of such a system which will be simple in construction and inexpensive to manufacture, by reason of its ready application and adaptation to the ordinary clocks which form a part of the accessory equipment of motor vehicles.

Other noteworthy features and characteristics of the improvements hereinafter claimed will be made apparent to those skilled in this art by a perusal of the following description and exemplary embodiment

illustrated in the accompanying drawings, forming a part thereof, in which—

Figure 1 is an external plan view of the timing device which forms one of the essential parts of our improved lighting system. Fig. 2 is a horizontal section of the timing device, on the plane 2—2 in Fig. 3. Fig. 3 is a side elevation of the timing device, showing the enclosing casing in section. Fig. 4 is a horizontal section, on the plane 4—4 in Fig. 3. Fig. 5 is a horizontal section, on the plane 5—5 in Fig. 3. Fig. 6 is an underside plan view on the plane 6—6 in Fig. 3. Fig. 7 is a sectional view on the plane 7—7 in Fig. 4. Fig. 8 is a side elevation of the timing device, on the plane 8—8 in Fig. 2. Fig. 9 is an enlarged detail underside plan view, showing the relative positions of the cam and disk wheel at one period of time. Fig. 10 is a fragmentary detail view of the parts shown in Fig. 9, in which the parts are shown in an advanced position from that illustrated in Fig. 9. Fig. 11 is an enlarged sectional detail view of the upper portion of the mechanism for operating the hands of the clock. Fig. 12 is a fragmentary detail perspective view of the contact finger for opening and closing the electric circuit. Fig. 13 is a diagrammatic view of our improved system for alternately lighting and extinguishing the lamps in the system.

Referring to the drawings, the lighting system, in view of its ready adaptation for motor vehicle use, will, for convenience, be described in connection with such a vehicle, and contemplates the utilization of a distributing system which comprises a number of suitably arranged conductor wires; a battery for supplying the electric current; a manually operated switch for interrupting the current, and an automatic timing device for automatically interrupting the electric current at stated intervals. When the lighting system is set for automatic operation the electric current passes from a battery 10 over a conductor wire 11 leading to a binder post 12 of a manually operated switch 13; thence over a switch arm 14 to a binder post 15, and thence over a conductor wire 16 to a binder post 17 of the timing device. When the circuit is closed the current passes through certain mechanism of the timing device, to be hereafter

more particularly described, to a binder post 18 and thence over conductor wire 19 which extends to the negative pole of battery 10. Lamps 20 are arranged in conductor wire 19 between the timing device and battery 10. The lighting system, in addition to its automatic operation is susceptible of manual operation in the usual way. This we accomplish by manually shifting switch arm 14, of switch 13, from binder post 15 to binder post 13^a, so that the current is shunted around the timing device over conductor wire 21.

The timing device of the system contemplates the utilization of any suitable clock mechanism, such as form a part of the accessory equipment located on the instrument board A of motor vehicles. As shown in Figs. 3 and 8 of the drawings, the timing device comprises a frame-work consisting of a number of spaced division walls 25, 26, 27, 28 and 29, which are held in spaced relation by means of the spacer bolts 30. This frame-work is enclosed in a casing 32 and forms the support for the various movable parts of the timing device. These movable parts include the usual main spring which is housed in and rotates a drum 35 as the spring unwinds, and through which the movable parts are operated. This enforced movement of the parts is accomplished by providing drum 35 with externally located teeth 36 which mesh with a pinion 37 (Fig. 8) mounted on a shaft 38, and this shaft is further provided with a second pinion 39 which meshes with and operates a pinion 40 arranged on a shaft 41. Shaft 41 is provided with a second pinion 42 which meshes with a pinion 43 arranged on the minute-hand shaft 44 for moving the minute-hand 45. Shaft 44 is also provided with a second pinion 46 which drives the hour-hand 47 through a train of speed reducing pinions 48, 49 and 50, which mechanism is common in clock construction.

The power for operating our improved cut out mechanism, for opening and closing the electric circuit, is taken from pinion 50, which drives the hour-hand 47, by means of an intermediate pinion 55 which meshes with a pinion 56 secured to a power transmission shaft 57 extending back of the clock mechanism. Shaft 57 is provided with a second pinion 58 which meshes with and drives a relatively larger gear wheel 59, the difference in ratio of the pinion 58 and gear wheel 59 being such as to cause the latter to make one complete revolution while hour-hand 47 makes two complete revolutions about its axis, and the purpose of this difference in the travel of these parts will be hereinafter described. Gear wheel 59 is arranged on and moves with a shaft 60 having its ends insulated free from the adjacent division walls 28 and 29 of the

frame work, and shaft 60 is further provided with a pair of disk wheels 61 and 62, the disk wheel 61 affording the means through which an electrical contact is effected and maintained with the free end of 70 a conductor arm 63 (Fig. 4) attached to a post 64 having its outer end formed into a binding post 17 for connecting the conductor wire 16 of the lighting system. Post 64 is insulated free from division walls 28 75 and 29 to prevent leakage, so that the current entering over wire 16 will pass through post 64 and arm 63 to energize disk wheels 61 and 62, gear wheel 59 and their supporting shaft 60. The current is 80 also prevented from escaping through the engagement of gear wheel 59 and its driving pinion 58 by insulating the latter from its shaft 57. Examining Figs. 7 and 9 it will be observed that disk wheel 62 is provided with an independently formed rim 62^a which is insulated free from the central and energized portion of disk wheel 62 by means of an intervening layer of insulating material 65 to provide a positive break in the electric current, so that rim 62^a may be free from the electric current until a contact is effected between it and the main body of the disk wheel 62. Such an electrical contact may be established between rim 62^a and disk wheel 62 by means of a contact finger 66 when the latter is moved into proper position with a manually operable cam-wheel 67. Contact finger 66 is pivotally mounted on and is carried around with disk wheel 62, and the contact finger is oscillated to open the circuit when its right angle extension 66^a contacts an extended portion 67^a of the manually operated cam-wheel 67, and the duration of this contact depends upon the length of the extended portion 67^a of said cam-wheel 67. Cam-wheel 67 is formed integrally with a sleeve 68 (Fig. 7) which is supported on shaft 60 carrying the disk wheels 61 and 62, but the sleeve 68 and its cam-wheel 67 are 100 susceptible of independent manual operation of shaft 60 and are insulated free from it to prevent leakage of the current through cam-wheel 67 when the latter is in contact with contact finger 66. See Fig. 7. When cam-wheel 67 oscillates contact finger 66 its outer end will move out of contact of a lug 62^b formed on rim 62^a and effect an interruption in the electric circuit, and when the contact finger has been carried a sufficient distance by the disk wheel to effect the disengagement of its right angle extension 66^a from cam-wheel 67 the said contact finger 110 will be oscillated under the influence of a spring 69 to again bring its outer end into contact with lug 62^b and close the circuit in the system. When the circuit is thus closed the current passes from disk wheel 62 through contact finger 66 to rim 62^a 120 130

from whence it passes out through a collector-arm 70 to post 71 and over conductor wire 19, through lamp 20 and back to battery 10. Post 71 is insulated free from 5 the division walls 28 and 29 to prevent leakage of the current, and the outer end of post 71 is formed into a binder post 18 to which conductor wire 19 is attached. The duration of time for maintaining the electric 10 circuit in open or closed condition is determined by the length of the contact between contact finger 66 and cam-wheel 67 and this is determined by the length of the extended portion 67^a of the cam-wheel. As an illustration, we have diagrammatically shown 15 cam-wheel 67, in Fig. 9, as being arbitrarily divided radially into twenty-four uniformly spaced parts, this number corresponding approximately to the number of hours constituting a day of time, and to insure that 20 the electric circuit will be kept closed throughout the longest period of darkness of a given day (within the confines of the United States) we have allotted fourteen- 25 twenty-fourths of the peripheral length of cam-wheel 67 to its less radial portion, so that the contact finger will be free of the cam-wheel and the circuit closed while the contact finger traverses this peripheral 30 portion of the cam-wheel, while the remaining ten-twenty-fourths of the periphery of the cam-wheel is allotted to its greater radial portion which actuates contact finger 66 to hold the circuit open. Hence, if the 35 portion 67^a of the cam-wheel is lengthened or shortened from that shown in Fig. 9 a corresponding increase or decrease in the herein described periods of time results.

In manually re-setting the hands of the 40 clock the disk wheel 62 and its contact finger 66 are simultaneously re-set, so that if the hands of the clock be set to indicate 3 p. m. (Fig. 1) six hours of the time for maintaining an open circuit has passed with four 45 remaining; this being followed by a period of fourteen hours during which time the circuit remains closed, so that lamp 20 will be lighted at 7 p. m. and extinguished at 9 a. m. next day. Under the above-men- 50 tioned arbitrary division of periphery of cam-wheel 67 the latter will hold the contact finger 66 in a position to effectively maintain an open circuit for a period of ten hours and then release the contact finger for 55 maintaining a closed circuit for a period of fourteen hours, and these movements for alternately opening and closing the circuit are continued in successive order.

To effect a manual re-setting of indicator 60 hand 75 and cam-wheel 67, the operator manually moves indicator hand 75, by means of a pinion 76 and a train of pinions 77, 78 and 79, until it points to the numeral "7" on the clock dial, so that the circuit in 65 the system will close four hours later, or

at 7 p. m. As the operator is re-setting indicator hand 75 to the desired point on the dial of the clock he simultaneously moves cam-wheel 67 into proper relation with contact finger 66 so as to bring about 70 the disengagement between the contact finger and the extended portion 67^a of the cam-wheel at the end of a four hour advance travel of said contact finger. To synchronize the movements between the indicator 75 hand 75 and cam-wheel 67 we mount pinion 77 on a shaft 82 (see Fig. 8) and this shaft is provided with a second pinion 83 which meshes with and drives a gear-wheel 84 mounted on the sleeve 68 carrying the cam-wheel 67. Pinion 83 is insulated away from its shaft 82 so as to prevent leakage of the current at that point.

As the time for automatically lighting lamp 20, to meet the increase in the number 85 of hours of darkness which will hardly exceed more than four—4 p. m. to 8 p. m.—we limit the distance of travel of the manually actuated pinion 76, so as to maintain a proper working relation between indicator 90 hand 75 and cam-wheel 67 and insure the closing of the circuit between the hours of 4 and 8 p. m. The means for limiting the movement of pinion 76, and therethrough indicator hand 75, is accomplished by a 95 pinion 76^a which is arranged on pinion 76 with its free end projecting through a slot 90 in the face-plate 91 of the clock, as indicated in Fig. 1, this slot being of a length 100 to permit only the maximum travel of said pinion.

The timing mechanism is also provided with an indicator to determine, if the clock ceases to function, whether the clock stopped during the a. m. or p. m. period of the day. 105 It is essential for the operator to know, when re-setting both the hands of the clock; the disk wheel 62, and the contact finger 66, that contact finger 66 has been brought into proper relation with cam-wheel 67, so as to insure the opening and closing of the circuit at the desired time. For the purpose of indicating the a. m. and p. m. periods of the day we employ a disk-pinion 95 (Fig. 2) 110 having its exposed surface divided into a light and dark area, the light area indicating the a. m. period and the dark area indicating the p. m. period. Pinion 95 is driven from the clock mechanism to bring its light and dark areas alternately into registration with a sight-opening 96 (Fig. 1), through which the operator may observe 115 which part of the pinion is visible at the time. Pinion 95 is driven directly from a pinion 50^a which is a part of the clock pinion 50 that moves the hour-hand 45 of the clock, so that if the clock ceases to function further movement of pinion 95 ceases. Hence, if the operator discovers that the 120 clock ceased running at 4 o'clock, as shown 125 130

by the clock hands, he can determine, by observing which part of pinion 95 is visible through sight-opening 96, whether the clock ceased running at 4 p. m. or at 4 a. m. Since there is a difference in the rate of travel between the hands of the clock and the disk wheel 62, it is necessary after the clock stops to re-set disk wheel 62 so as to bring pawl 66 into proper position relatively to cam-wheel 67 at the same time the hands of the clock are being re-set to indicate the proper hour of the day, and this is made possible through the mechanism heretofore described in conjunction with the exposure of the light and dark areas of pinion 95 through sight-opening 96. As an illustration: If at 9 a. m. the operator notes that the clock ceased running at 4 o'clock and that the dark portion of pinion 95 is visible through sight-opening 96, he will know that the clock ceased running at 4 p. m. If the operator made this discovery within twelve hours from the time the clock stopped it will only be necessary to move the hands of the clock in a clockwise direction until they indicate the hour of setting; but in the above mentioned illustration seventeen hours have lapsed between 4 p. m. and 9 a. m. In this instance, after the operator has moved the hands of the clock in a clockwise direction from 4 (the hour the clock stopped) until 9, an advance of 5 hours, he will observe that the dark area of pinion 95 is still visible through sight-opening 96, so that the hands of the clock must be advanced an additional twelve hours—a total of seventeen hours—which will denote 9 a. m. the hour of setting and which will be verified by the light area of pinion 95 now visible through sight-opening 96, and he will also know that disk wheel 92 and its contact finger 66 have been brought into proper position relatively with the manually operated cam-wheel 67.

The foregoing description is merely illustrative of the principles of our invention, and other modifications thereof may be made that will function in substantially the same manner without departing from the spirit of the invention, and we do not, therefore, desire to limit ourselves to the use of any specific form of the parts illustrated.

Having thus fully described our said invention, what we desire to secure by Letters Patent, is—

1. In combination with a clock mechanism, means for indicating time, a contact finger mounted on support driven by the clock mechanism, a rotatable cam for oscillating the contact finger, and means for changing the relative position of the cam and contact finger for varying the time of opening and closing a circuit, substantially as set forth.

2. The combination with a clock mechanism, means for indicating time, an auto-

matic cut out mechanism mounted on a support driven from the clock mechanism, means for oscillating the cut out mechanism, and means for manually changing the position of the last-named means relatively to the cut-out mechanism for changing the time of opening and closing the circuit, substantially as set forth.

3. In combination with a clock mechanism, means for indicating time, automatic circuit opening and closing means driven by the clock mechanism, said last mentioned means comprising a plurality of rotary disks, one of said disks having a rim insulated from its body, an oscillatory contact finger carried by the body and having one end extending over the insulated rim, the other end of said contact finger having an arm normally tensioned against the periphery of another of said disks, said last mentioned disk having cam surfaces adapted to actuate said oscillatory arm for opening and closing the circuit, substantially as set forth.

4. In combination with a clock mechanism, means for indicating time, automatic circuit opening and closing means driven by the clock mechanism, said last mentioned means comprising a plurality of rotary disks, one of said disks having a rim insulated from its body, an oscillatory contact finger carried by the body and having one end extending over the insulated rim, the other end of said contact finger having an arm normally tensioned against the periphery of another of said disks, said last mentioned disk having cam surfaces adapted to actuate said oscillatory arm for opening and closing the circuit, and a conductor arm engaging the insulated rim for maintaining electrical connection between the periphery of said rim and a binding post, substantially as set forth.

5. A switch comprising a shaft, a rotary disk on said shaft, a conductor arm engaging said disk, a second disk on said shaft having a rim insulated from its body, a contact element carried by the body and adapted to be moved into engagement with said insulated rim, a second conductor arm engaging said rim and means for operating said contact element to complete the circuit, substantially as set forth.

6. A switch comprising a shaft, a rotary disk on said shaft, a conductor arm engaging said disk, a second disk on said shaft having a rim insulated from its body, a contact element carried by the body and adapted to be moved into engagement with said insulated rim, a conductor arm engaging said rim and means for operating said contact element to complete the circuit, and means for changing the relative position between the contact element and its operating means for varying the time of

opening and closing the circuit, substantially set forth.

7. In combination with operating mechanism, automatic circuit opening and closing means driven by said operating mechanism, said automatic circuit opening and closing means comprising a shaft, a rotary disk on said shaft, a resilient conductor arm engaging the periphery of said disk, a second disk on said shaft having a rim insulated from its body, an oscillatory contact element carried by said body extending ad-

jacent the insulated rim, a resilient conductor arm engagement with the periphery of said rim and another disk on said shaft having its periphery forming a cam face adapted to operate said contact element for closing the circuit, substantially as set forth. 15

In witness whereof, we have hereunto set our hands and seals at Indianapolis, Indiana, 20 this 1st day of May, A. D., one thousand nine hundred and twenty-two.
